UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

TIE-TAMPER FRONT-END CONSTRUCTION.

Application filed November 9, 1920. Serial No. 422,845.

To all whom it may concern:

Be it known that I, FRANCIS A. JIMERSON, a citizen of the United States, and a resident of Athens, county of Bradford, State of Pennsylvania, have invented certain new and useful Improvements in Tie-Tamper Front-End Constructions, of which the following is a specification.

This invention relates to fluid actuated tie tampers of the hammer type, having a fluid pressure cylinder, and a tamper steel having a collared shank adapted to extend into the cylinder in position to receive the impact blow of the hammer. The shank of the tamper steel may pass through a suitable loose bushing, usually referred to by manufacturers and users as a "nozzle," forming a chuck located forwardly of the collar, and means have heretofore been provided around the steel shank and between the said bushing and the enclosing barrel nut for cushioning the shock due to the collar striking the inner end of the bushing.

This cushioning means has usually been in the form of a spring, but such springs have been found to break and are short lived. It has furthermore been found to be practically impossible to make springs of suitable sizes which will continuously withstand the severe shock to which they are subjected without weakening, and injury to the machine has resulted from such breakage, with the attendant delays in the work.

The primary object of the present invention is to secure a simple and efficient cushioning device which cannot break under all ordinary circumstances and will be long lived and save breakage and repairs. I have found that a properly constructed split bushing retaining rubber buffer or buffer of similar material has many advantages over a cushioning spring. The rubber buffer should be of comparatively soft pliable vulcanized rubber, rather than hard rubber and should have appreciable elasticity. The rubber buffer is located within the barrel nut forming the front head of the tie tamper and a split metallic buffer washer is preferably arranged between the buffer and the outer end of the barrel nut over the opening in the end of the barrel nut through which the collared shank of the tamper steel passes in assembling the parts, so that said washer closes the opening, protects the buffer and

prevents the buffer from squeezing through the hole in said end.

The tie tamper front end construction and cushioning device are illustrated in one of their preferred forms in the accompanying drawings, in which—

Figure 1 is a longitudinal sectional elevation of the front end of a machine containing the invention.

Figure 2 is a side elevation, and

Figure 3 is a detail side view of a portion of the shank of a tamper steel illustrating the method of applying the buffer and washer to the shank.

Referring to the drawings, only so much of the front end of a fluid actuated tie tamper of the hammer type is shown which will serve to illustrate the invention. The cylinder A, of which only the front end portion is shown, is adapted to receive the shank B of a tie tamper steel, in this instance, having a collar C. The shank extends through the sleeve D into position to receive the impact blows of the fluid actuated hammer E in the usual manner.

A flanged split bushing F loosely surrounds the shank of the steel forwardly of the collar C and extends into the front end of the cylinder A. The two parts of the split bushing F are formed with a flange G in this instance bearing against the outer end of the cylinder. Sufficient space is maintained between the opposed ends of the sleeve and split bushing to permit limited movement of the collar and steel in said space.

In accordance with this invention, a split non-metallic elastic bushing retaining rubber buffer H is loosely placed over the shank of the steel forwardly of the bushing F and is adapted to bear against the flange G of the bushing F to hold it in its rearward position in the front end of the cylinder. In Figure 3, the rubber buffer H is shown in position in full lines on the shank of the steel but is shown in dotted lines opened up sufficiently to permit the shank of the steel to be placed within the buffer and the elasticity of the buffer closes the buffer about the shank of the steel.

A split metallic buffer washer J of substantially the same diameter or slightly larger than the normal outside diameter of the buffer, is placed on the shank of the steel

in front of the buffer, and in Figure 3 the buffer washer is shown in position on the shank in full lines, and is shown in dotted lines in the act of being placed on the shank.

5 The split washer J is opened or forced apart as indicated in dotted lines and is thus sprung over the shank of the steel.

It is necessary that the bushing F, the rubber bushing retaining buffer H and the 10 buffer washer J all be split or divided in such manner that they may be placed over the shank of the steel, because of the fact that in a tie tamper, the tamper steel is provided with a broadened tamper end K and 15 such parts as the bushing F, the buffer and the washer could not be conveniently or practically constructed to be placed over the shank of the steel from either end. A barrel nut L forming the front head of the tie 20 tamper encloses the buffer and washer as illustrated particularly in Figure 1, and extends over the front end of the cylinder A. The outer end O of the barrel nut is provided with an aperture P of sufficient size 25 to permit the entrance of the collar C of the steel and the buffer washer J between the buffer H and the end O of the barrel nut closes this opening when the parts are 30 assembled, protects the buffer, prevents the buffer from becoming distorted and damaged by shock and pressure which would otherwise tend to force the material of the buffer through the aperture P.

A portion of the body of the barrel nut L 35 is preferably slotted or slit at Q and this slit portion is provided with lugs R adapted to receive the tightening bolt S having the nuts T and locking washer U. The barrel nut is preferably threaded onto the outer 40 end of the cylinder A by means of the screw threads V and suitable means may be provided for retaining or locking the barrel nut in position after it is tightened, in this instance the inner edge of the barrel nut 45 being provided with grooves or notches W adapted to receive the bent end X of a coiled spring Y the other bent end Z of which enters the notch a in the flange b on the cylinder A.

50 After the parts are assembled and the barrel nut L is adjusted and tightened and retained in position, the shock of the collar C upon the inner end of the bushing F is cushioned by the bushing retaining rubber 55 buffer H which has a double function of a cushion and a retaining device. The split buffer washer J also has the double function of a retaining and protective device. This cushioning device has been found to operate 60 satisfactorily and well, prolongs the life of the parts and does not need to be renewed except in occasional instances.

I claim:

65 1. A fluid actuated tie tamper of the hammer type, having a fluid pressure cylin-

der, a tamper steel having a collared shank adapted to extend into the cylinder in position to receive the impact blows of the hammer, a split bushing loosely surrounding the shank of the steel forwardly of said collar and extending loosely into the front end of the cylinder, a sleeve surrounding the steel and extending into the cylinder rearwardly of said collar, whereby the collar on the steel has limited movement 70 between said split bushing and sleeve, a split bushing retaining elastic buffer loosely mounted on the shank of the steel forwardly of said bushing yieldingly holding the split bushing in its rearmost 75 position in the front end of the cylinder, a split metallic buffer washer in front of the said buffer, a barrel nut enclosing said buffer and washer and extending over the front end of the cylinder, and means for 80 retaining said barrel nut in position on the cylinder.

2. A fluid actuated tie tamper of the hammer type, having a fluid pressure cylinder, a tie tamper steel having a collared shank 85 adapted to extend into the cylinder, in position to receive the impact blows of the hammer, a flanged split bushing loosely surrounding the shank of the steel forwardly of said collar and extending loosely into the front end of the cylinder, the bushing flange bearing against the outer end of the cylinder, a sleeve surrounding the steel and extending into the cylinder rearwardly of 90 said collar so that the collar on the steel has limited movement between the said split bushing and the said steel, a split bushing retaining elastic buffer on the shank of the steel adapted to bear against the flange of the bushing, and yieldingly holding the split bushing in its rearmost position in the front end of the cylinder, a split metallic 95 buffer washer on the shank of the steel in front of the said buffer, a barrel nut enclosing said buffer and washer and extending over the front end of the cylinder, the said barrel nut having an opening in its front end to permit the entrance 100 of the collar on the steel, and the buffer washer forming a closure for said opening when the parts are assembled, means for tightening the barrel nut on the cylinder, and additional means for retaining the nut in position.

3. A fluid actuated tie tamper of the 105 hammer type, comprising a cylinder and reciprocating hammer piston, a sleeve within the front end of the cylinder, a tamper steel having a collared shank adapted to extend through said sleeve into the cylinder in position to receive the direct blows of impact of the hammer piston, a removable split bushing loosely surrounding the steel and located within the cylinder wholly in front 110 of the collar on the steel, sufficient space 115

being maintained between the opposed ends of the sleeve and split bushing to permit limited movement of the collar and steel in said space, a split nonmetallic elastic buffer 5 loosely surrounding the shank of the steel forwardly of said bushing for holding the split bushing in its rearmost position in the front end of the cylinder, a split metallic buffer washer in front of said elastic buffer, 10 a barrel nut enclosing said buffer and washer and extending over the front end of the cyl-

inder, the said barrel nut having an opening in its front end to permit the entrance of the collar on the steel, and the buffer washer forming a closure for said opening when the 15 parts are assembled, means for tightening the barrel nut on the cylinder, and additional means for retaining the nut in position.

In testimony whereof I have signed this 20 specification.

FRANCIS A. JIMERSON.
